UNITED STATES PATENT OFFICE

2,415,463

RAZOR BLADE SHARPENER

Frank R. Chester, Manhattan Beach, Calif.

Application October 9, 1944, Serial No. 557,877

5 Claims. (Cl. 51—80)

1

My present invention relates to a razor blade sharpener.

One of the principal objects of this invention is to provide a simple and portable device whereby safety razor blades may be sharpened by hollow-grinding the cutting edges thereof.

An important object also of this invention is to provide such a safety razor blade sharpener which is economical to make, easy to operate, one requiring no adjustments, and one which will not readily deteriorate or get out of order.

Another important object of this invention is to provide a sharpener of this class into which the safety razor blade may be easily and correctly placed, and readily and securely held while sharpening the same.

A further important object is to provide novel and simple means of operating cylindrical sharpening or honing elements in a sharpener of this class.

A novel and important feature of this invention is the provision of screw-like interlocking cylindrical sharpening elements or rollers, which are rotatable in the same direction and between which the edge of a safety razor blade may be loosely positioned and easily retained, and against the cutting edge of which a substantially continuous sharpening surface or means is applied.

A further novel important feature of this invention is the provision of sharpening means which is periodically reversed transversely and longitudinally of the cutting edge.

With these and other objects in view, as will appear hereinafter, I have devised a sharpener particularly adapted for safety razor blades, and one having certain novel features of construction, combination, and arrangement of parts and portions, as will be hereinafter described in detail and particularly set forth in the appended claims, reference being had to the accompanying drawing, and to the characters of reference thereon, which form a part of this application, in which:

Fig. 1 is an end view of my sharpener in a preferred form;

Fig. 2 is a sectional view thereof, taken through 2—2 of Fig. 1;

Fig. 3 is an enlarged sectional view thereof, taken through 3—3 of Fig. 4;

Fig. 4 is a transverse sectional view thereof, taken through 4—4 of Fig. 3; and,

Fig. 5 is an enlarged fragmentary view showing in greater detail the hinged blade retainer, shown in Fig. 2.

2

My razor blade sharpener, as shown in the drawing, is carried in an enclosure or case 1 which is adapted to be drawn along and adapted to be operated by a cord 2.

5 The case is relatively long and is of substantially triangular cross-section with rounded corners. That is, the case is of substantially prismatic shape. The opening or slit, designated 1^a, for inserting the razor blade to be sharpened, designated B, is located at the top and at one of the apex portions.

10 The operating cord 2 is positioned at one end of the case and extends from the opposite sides and near the bottom thereof.

15 Within the case are provided two razor blade sharpening elements or rolls 11 and 12. These are arranged on parallel axes and are located near the bottom and at the opposite sides of the vertical plane passing through the slit 1^a. That is, they are located within the two lower apex portions 1^b and 1^c of the case.

20 The sharpening elements or rolls 11 and 12 may be made of a suitable abrasive material, and they are supported on arbors 11^a and 12^a, 25 which are mounted in the end walls 1^d and 1^e of the case. These rolls are preferably made identical in form, and they are screw-like, being spirally fluted. The spiral flange or ridge portions 11^b and 12^b of the respective rolls 11 and 30 12 extend into the spiral flutes 12^c and 11^c of the adjacently positioned rolls. The outer faces of the ridges 11^b and 12^b are flat, and these portions engage and hollow-grind the edge portions of the blade, as shown best in Fig. 4.

35 At the coincident ends of the rolls 11 and 12, and coaxial therewith are provided gears 13 and 14, respectively, the outside diameter of these gears being less than the diameters of the sharpening rolls. Each of these gears mesh with and 40 are driven by a larger gear 15 revolvably mounted on a stud 16 secured to the end wall 1^d of the case.

45 Forming a part of and coaxial with the gear 15 is a drive sheave 17. This sheave is driven by the cord 2 as the sharpening device is moved along the cord. On the arbors 11^a and 12^a, and beyond the outer sides of the gears 13 and 14, are idler sheaves 18 and 19 which guide the cord 2 around the drive sheave 17, and they also guide 50 the end portions of the cord from the case. Thus movement of the device along the cord 2 causes the latter to be guided around and to rotate the sheave 17.

The edge of the blade B to be sharpened is inserted, between the adjacent portions of the

sharpening rolls 11 and 12, through the slit 1^a of the case. The blade is yieldably held in such sharpening relation with the rolls 11 and 12 by means of a blade retainer 20 which is pivoted at one end to the case beyond one end of the slit 1^a. It is adapted to be resiliently held in a position over the slit by means of a spring 21.

By reason of the rotation of the sharpening rolls in the same direction, one of the rolls tends to draw the edge of the blade between the rolls, but the other roll tends to force the blade outwardly. Thus a slight pressure on the outer edge of the blade tends to hold the blade in sharpening position between the rolls.

Though I have shown and described a particular construction, combination, and arrangement of parts and portions, I do not wish to be limited to the same, but desire to include in the scope of my invention the construction, combination, and arrangement substantially as set forth in the appended claims.

I claim:

1. In a sharpener, a pair of like spirally-fluted sharpening rolls arranged on parallel axes with the ridge portions between the flutes of one element extending into the flutes of the other, and means for rotating the elements in the same direction.

2. In a sharpener, a pair of like spirally-fluted sharpening rolls arranged on parallel axes with the ridge portions between the flutes of one element extending into the flutes of the other, means for rotating the elements in the same direction, and means for operating the latter means alternately in opposite directions.

3. In a sharpener, a pair of cylindrical sharpening elements arranged on parallel axes, a gear fixed at the coincident ends of and coaxially with each sharpening element, a third gear meshing with both of the first gears for rotating both elements in the same direction, a sheave fixed coaxially to the third gear, idler sheaves rotatably carried by and coaxially with said sharpening elements, and a cord extending over the idler sheaves and around the sheave on the third gear.

4. In a sharpener, an enclosure, a pair of cylindrical sharpening elements arranged on parallel

axes within the enclosure, a gear fixed at the coincident ends of and coaxially with each sharpening element, and a third gear meshing with both of the first gears for rotating both elements in the same direction, a sheave fixed coaxially to the third gear, idler sheaves rotatably carried by and coaxially with said sharpening elements, and a cord for operating the sharpening elements, the intermediate portion of the cord extending around the sheave on the drive gear and thence over the idler sheaves, the end portions of the cord extending from the opposite sides of the enclosure.

5. In a sharpener, an enclosure, a pair of adjacently positioned cylindrical sharpening elements arranged on parallel axes within the enclosure, means for holding a blade within the enclosure in sharpening relation to both of said sharpening elements, said elements being positioned so as simultaneously to sharpen both sides of the edge of the blade positioned therebetween, said enclosure being so constructed and arranged to be freely reciprocated, means for rotating the elements in the same direction with respect to each other, and means in association with the enclosure for rotating the element-rotating means alternately in opposite directions when the enclosure is reciprocated.
